UNITED STATES PATENT OFFICE.

CURTIS L. MOODY AND THOMAS MIDGLEY, OF SPRINGFIELD, MASSACHUSETTS.

DESIGN FOR A TIRE.

54,114.

Specification for Design.

Patented Nov. 4, 1919.

Application filed March 20, 1919. Serial No. 283,937. Term of patent 14 years.

To all whom it may concern:

Be it known that we, CURTIS L. MOODY and THOMAS MIDGLEY, citizens of the United States, residing at Springfield, in the county of Hampden and State of Massachusetts, have invented a new, original, and ornamental Design for Tires, of which the following is a specification, reference being had to the accompanying drawing, forming part thereof.

Figure 1 is a fragmentary plan view of a tire showing our new design; and

Fig. 2 is a cross section of a tire taken on line 2—2 of Fig. 1.

We claim—

The new, original, and ornamental design for a tire, as shown.

CURTIS L. MOODY.
THOMAS MIDGLEY.
